Specification of Letters Patent.

Patented Nov. 7, 1916.

Application filed October 11, 1915. Serial No. 55,212.

To all whom it may concern:

Be it known that I, OSCAR F. WESTENHISER, a citizen of the United States, residing at St. Louis, State of Missouri, have invented certain new and useful Improvements in Presses, of which the following is a full, clear, and exact description, reference being had to the accompanying drawings, forming a part hereof.

10 My invention has relation to improvements in presses; and it consists in the novel features of construction more fully set forth in the specification and pointed out in the claims.

15 The present is an improvement on a form of press commonly employed for pressing a number of out-soles with their complement of "slips" or linings, for the purpose of cementing the parts together, examples of

20 which press may be found in U. S. Letters Patent numbered 1,098,699, dated June 2, 1914, granted jointly to myself and William P. Jones, the object of the present invention being to provide such a press with a

25 special form of locking or gripping device by which the telescoping members of the press between which the stock is compressed may be held against separation when the final pressure on the stock is applied; to

30 provide a locking device which will permit instantaneous disengagement of the press members when the stock is to be removed; to simplify the construction of the press as a whole, and to provide other features of construction the advantages of which will fully appear from the following detailed description of the invention in connection with the accompanying drawings in which—

Figure 1 is a side elevation of the press with stock shown dotted; Fig. 2 is an end elevation of the press with stock removed; Fig. 3 is an enlarged end elevational detail of the loop or strap of one of the press members through which operates the grooved arm of the telescoping member; Fig. 4 is a view similar to Fig. 3, but with the outer wall of the loop or housing removed, the housing being shown in vertical section; Fig. 5 is a combined inside elevational view and vertical section on the zig-zag line 5—5 of Fig. 3, of the telescoping arms of the press members or sections; and Fig. 6 is a cross-section on the line 6—6 of Fig. 3.

Referring to the drawings, 1 represents a U-shaped member the arms whereof terminate in loops or straps 2, provided with pas-

sage-ways *p* for the traverse of the arms of a complementary telescoping U-shaped member 1', the outer faces of whose arms are provided with transverse corrugations *a*. 60 Mounted rotatably in the side walls of the straps or loops 2, about axes disposed parallel to the longitudinal axes of the corrugations *a* are cylindrical rocker-spindles 3 terminating at one end in a wing or lobe 4, the wings of the respective spindles being on opposite sides of the respective straps, that is to say, the wing on one spindle is on one side of the press, that on the opposite spindle being disposed on the opposite side of 70 the press for convenience of manipulating the press members or sections. The spindle 3 traverses a socket or recess *h* formed in the solid portion of the strap, said recess being in free communication with the passage *p* 75 as shown to best advantage in Fig. 4. Both sides of the press are alike so that a description of one side will answer for both. Secured to the spindle 3 and operating in the recess or socket *h* is a dog or block or equivalent catch 5 (the spindle having a drive fit through the dog) which for a certain inclined position is adapted to engage the corrugations *a* of the adjacent arm of the U-shaped member 1, thereby locking the member against an outward or expanding movement, the dog 5 and corrugations *a* acting very much on the principle of a pawl and rack-bar. The tendency of the dog is to present its lower free edge to the corrugations *a* 80 by reason of the draft of the coiled contracting spring 6 one end of which is secured to a lug 7 disposed to one side of the rotation axis of the wing 4 at the inner end of the wing, the opposite end of the spring being 85 coupled near the base of locking latch or pawl 8 hinged to the side face of the strap 2, a securing screw 9 serving as the fulcrum for said pawl, the latter being mounted loosely about said screw 9. The edge of the 90 pawl facing the wing 4 is undercut leaving an outer terminal lobe formation or finger hold *s* by which the pawl may be readily seized and lifted for purposes of manipulation. Along the undercut edge of the pawl 100 8 is formed a notch or recess *r*, said pawl operating to engage the adjacent edge of the wing 4 when the latter is oscillated sufficiently to bring the outer face of the block or dog 5 into parallelism with the arm of the member 1', that is, parallel to the direction 105 of movement of said arm, when the block or

dog will be wholly disengaged from the corrugations *a*, thus permitting the member 1' to be freely withdrawn from the loops or straps of the member 1. The outward movement of the pawl 8 is limited by a pin 10 as shown.

The cross-bar of the bottom U-shaped member of section 1 is provided with a board of stock-supporting platform P, the sides of which are provided on either side of the member 1 with anchoring or fastening loops 11 for securing the detachable ends of the cords 12 passed around the stock S to be pressed, the opposite ends of the cords being permanently secured to the opposite side of the platform by means of nails or screws 13, as fully shown and described in my pending application for shoe-sole press attachments Serial Number 875,669, filed December 5, 1914. The stock is held in position between the bottom platform P and the upper presser-plate P' which is loosely connected to the upper cylindrical cross-bar of the member 1' by a U-shaped bracket 14 the terminal arms of which are provided with vertically elongated slots *m* to afford free vertical play to the presser-plate to and from the stock S. The presser-plate is controlled by the cams C of an actuating lever 15 pivoted about the cross-bar of the member 1' between the slotted arms of the bracket 14, the arrangement being on the order described in my U. S. Letters Patent 1,126,325, dated January 26, 1915.

The operation of the press is substantially as follows: Let us assume that the stock S is placed on the platform P and securely tied by the cords 12 in readiness to be compressed. Let us further assume that the upper section or press member 1' is wholly withdrawn from the loops or straps 2. The stock being in position on the platform P, the operator inserts the arms of the member 1' into the passage-ways *p* of the straps, the corrugations *a* freely riding over the inner edges of the dogs 5, the same as a ratchet rides freely over a pawl in a given direction. The wing 4 when released assumes the position shown in Fig. 3 under the tension of the spring 6, and when the arm of the member 1' is inserted into the passage *p* of the loop 2, the dog 5 is readily oscillated to make way for the arm, the dog being tripped to cause the wing 4 to assume an intermediate position shown by the dotted lines in Fig. 3, that is to say a position wherein the upper edge of the wing comes between the lobe *s* and recess *r* of the locking pawl 8. When the member 1' has been inserted (through the loops 2) sufficiently to cause the pressure-plate P' to engage the upper surface of the stock S, the operator swings the lever 15 to the right (see arrow Fig. 1) or in proper direction to cause the cams C to force the plate firmly against the

stock, thus compressing the latter. The reaction of the stock thus compressed between the members P, P', tends to force the members 1, 1', apart (see arrows Fig. 3), causing the dogs 5 to exert a grip on the corrugated faces of the arms of the member 1', and preventing movement of said member. Thus the stock remains under compression until permanently set, or until the slips are firmly adhered to the out-soles. An inspection of Fig. 3 shows that the member 1' is freely insertible into the loops 2 of the member 1 (the dogs 5 freely yielding in response to such inserting movement) but is locked or gripped against an outward movement on account of the dogs gripping the corrugations *a* of said member. When the stock is finally compressed, and the slips thoroughly cemented, the operator rocks the spindles 3 by seizing the wings 4 and oscillating the latter until their upper edges (riding along the curved undercuts of the pawls) come opposite the recesses *r* of the pawls, when the springs 6 will automatically draw the recesses over the wings (Fig. 4) and cause the wings to be locked. When however, the wings 4 are in engagement with the recesses *r* of the pawls 8, the dogs 5 are in position as shown in Fig. 4, that is to say their outer faces are parallel to the arms of the member 1', and the dogs are wholly disengaged from the corrugations *a*, permitting the member 1' to be readily withdrawn from the loops 2, and the stock removed. To treat a fresh lot of stock, the operator first lifts and releases the pawls or latches 8 from the wings 4, thereby disengaging the latter from the recesses *r*, the tension of the spring 6 rotating and restoring the wings and dogs to the position indicated in Fig. 3, thus bringing the parts back to their original position, the loops 2 being free to again receive the arms of the member 1' and the dogs locking or gripping the same against outward movement, that is to say, a movement tending to separate the members 1, 1'. Before removing the member 1' at the conclusion of the cementing operation, it is best to swing the lever 15 back to its original position (Fig. 1) just prior to the disengagement of the wings 4 from the recesses *r* of the locking pawls 8.

Having described my invention what I claim is:

1. In combination with a pair of members connected telescopically with one another, a rotatable catch operating to grip one of the members and prevent movement between the members in one direction, a spring for normally maintaining the catch in gripping engagement with its member, and means coupled to the spring on the member supporting the catch for maintaining the latter out of engagement with the opposite member.

2. In combination with a pair of members in movable relation to one another, a rotatable catch on one member operating for a certain position to grip the opposite member against movement in a given direction, a contracting spring for rotating the catch to gripping position, and a movable member coupled to the spring for maintaining the catch in releasing position when turned from its gripping position against the tension of the spring.
3. In combination with a pair of members in movable relation to one another, a movable catch on one member operating for a certain position to grip the opposite member against movement in a given direction, a contracting spring for moving the catch to gripping position, and means coupled to said spring for maintaining the catch in releasing position when moved from its gripping position against the tension of the spring.
4. In combination with a pair of press members in slidable relation to one another, a rotatable catch on one member operating for a given position to grip the opposite member against movement tending to separate the members, a contracting spring for rotating the catch to gripping position, and a locking latch or pawl coupled to the spring operating to maintain the catch out of its gripping position upon rotation of the catch through a given arc.
5. In combination with a pair of press members in slidable relation to one another, a rotatable catch on one member, a contracting spring for rotating the catch in a given direction to grip the opposite member against a separating movement of the members, a latch hinged to the member carrying the catch and coupled to the spring aforesaid, a wing carried by the catch and riding freely along the latch, the latter being provided with a recess for automatically engaging the edge of the wing under the resilient action of the spring, the catch being held out of its gripping position while engaged by the recess aforesaid.
6. In combination with a pair of U-shaped press members, loops provided with longitudinal passageways on the arms of one member for slidably receiving the arms of
- the opposite member, a recess formed in the wall of each loop and opening into the passageway aforesaid, the inner faces of the 55 arms of the opposite press member being transversely corrugated and movable past the recesses aforesaid, a catch mounted rotatably across each recess and adapted for a certain position to engage the corrugations 60 of the arms inserted into the loops of the first member, a spindle for each catch, a wing on each spindle on the outside of the loop, a contracting spring coupled at one end to the wing at a point to one side of the 65 rotation axis of the catch, a latch hinged at one end to the wall of the loop at a point in proximity to the wing aforesaid, the opposite end of the spring being coupled to the latch at a point between the free end 70 and hinge axis thereof, the tension of the spring tending to rotate the catch into gripping engagement with the corrugations of the arm traversing the passageway of the loop, one edge of the wing riding freely 75 over the adjacent edge of the latch, the latter being provided along said edge with a recess at a point intermediate its free end and the point of connection of the spring therewith for receiving the edge of the wing 80 when the latter is turned opposite the recess, the latch automatically locking the wing and the catch whereby the latter is maintained out of gripping engagement with the corrugations aforesaid.
7. In combination with a pair of press members in slidable relation, a rotatable catch on one member operating to grip the opposite member against a movement tending to separate the members, a spring for 90 normally maintaining the catch in gripping engagement with its member, and a latch coupled to the spring for maintaining the catch out of engagement upon rotation of the catch through a given arc in a direction 95 opposite that in which it is rotated for gripping its member.

In testimony whereof I affix my signature, in presence of two witnesses.

OSCAR F. WESTENHISER.
